Primary Examiner — Richard E Chilcot*(74) Attorney, Agent, or Firm* — Cooper Legal Group, LLC; Ronald M. Kachmarik(57) **CLAIM**

The ornamental design for a bracelet, as shown and described.

DESCRIPTION

FIG. 1.1 is a perspective view of a bracelet, showing the new design;

FIG. 1.2 is a front view thereof;

FIG. 1.3 is a back view thereof;

FIG. 1.4 is a top view thereof;

FIG. 1.5 is a bottom view thereof;

FIG. 1.6 is a first side view thereof; and

FIG. 1.7 is a second side view thereof.

The broken line showings are included for the purpose of illustrating environment and form no part of the claimed design.
